JERRY C. LIBERTY, OF EASTHAMPTON, MASSACHUSETTS.

BOBBIN-FEELER STOP-MOTION FOR LOOMS.

1,124,044.

Specification of Letters Patent.

Patented Jan. 5, 1915.

Application filed January 9, 1914. Serial No. 811,184.

To all whom it may concern:

Be it known that I, JERRY C. LIBERTY, a citizen of the United States of America, and resident of Easthampton, in the county 5 of Hampshire and State of Massachusetts, have invented certain new and useful Improvements in Bobbin-Feeler Stop-Motions for Looms, of which the following is a full, clear, and exact description.

10 The object of this invention is to provide a stop motion for a loom which is operable for the stoppage of the loop when the thread or yarn on the bobbin of the loom shuttle becomes nearly exhausted so that 15 the loom cannot be run for one or any number of picks when there is no filling to be woven into the cloth.

The stop motion of the present invention is one which is employed in conjunction 20 with the usual weft stop motion, that is it contemplates the utilization of already known and also new instrumentalities as follows:—The lay provided with the shuttle box and the shuttle therefor, the weft fork 25 slide, the shipper with which the weft fork slide coacts and the weft fork hammer, a tiltable member pivotally mounted on the weft fork slide having an abutment adapted to be engaged by the weft hammer in simi- 30 lar manner to the engagement by such ham- 35 mer of the weft fork, a feeler member hav- 40 ing a position opposite the location of the shuttle box and adapted on the beating up movements of the lay to be successively 45 moved by the bobbin thread when the same 50 is present on the bobbin, but to be non-actuated or passive when there is an absence of 55 thread on the bobbin, and means actuated by the feeler member, and for swinging the 60 tiltable member of the weft fork slide for 65 carrying an abutment of such tiltable mem- 70 ber out of, or away from, the range of 75 movement of the weft hammer. And for 80 the carrying out of this invention in its 85 most advantageous manner, I employ a 90 shuttle bobbin of the particular construction 95 which will be hereinafter fully described.

The invention is described in conjunction 100 with the accompanying drawings and is 105 set forth in the claims.

In the drawings:—Figures 1 and 2 are 110 plan views showing the bobbin feeler stop motion in conjunction with the usual weft stop motion,—Fig. 1 representing condi- 115 tions whereby under a sufficiency of thread on the bobbin the feeler device will be suc-

cessively actuated and the loom continue its running, while Fig. 2 represents conditions whereby by reason of an exhausted condition of the thread on the bobbin the loom 60 will be stopped. Fig. 3 is a perspective view of the stop motion. Figs. 4 and 5 are sectional views through the weft fork slide under conditions respectively corresponding to those referred to in respect of Figs. 1 65 and 2. Fig. 6 is a view showing a slight modification in the relative arrangement of parts to be hereinafter referred to. Figs. 7 and 8 are respectively a plan view of the butt end portion of the bobbin and the sec- 70 tional longitudinal view thereof on line 8—8, Fig. 7.

Similar characters of reference indicate corresponding parts in all of the views.

In the drawings, A represents the breast 75 beam of the loom, B a portion of the lay comprising the shuttle box, C the weft fork slide in which the pivotally mounted weft fork D is carried, and E represents the shipper with which the weft fork slide coacts 80 and which through suitable or usual connections operates the clutch E² appurtenant to the main shaft of the loom.

In Figs. 4 and 5, G represents the weft hammer; and the devices here referred to 85 are the usual ones included in the most well known form of weft stop motions for looms and so operative that upon a breakage or failure of weft to be laid across the loom, the weft fork will not be swung to elevate 90 the tail or abutment a thereof, but will remain in the path of movement of the weft hammer to be engaged by the latter, resulting in the sliding movement of the weft fork slide and the operation of the shipper, 95 to stop the loom. There is pivotally mounted on the slide C a tiltable member J adjacent and forward of the weft fork and entirely independent thereof; and the same is provided with an actuating arm b for- 100 wardly offside from the pivot d, and it has an abutment or tail e adjacent the tail a of the weft fork.

K represents a bracket supported on the loom frame at the end of the breast beam 105 and opposite the location of the shuttle box, the same having upstanding apertured lugs f and g, and also made with a straight guiding slot h in a base portion thereof, which slot ranges in a line corresponding 110 to the line of movement of the lay.

M represents a feeler slide bar mounted

and guided through said lugs f , g , and it has a member i adjustably clamped or confined thereon, which member is formed with a bifurcated upper portion i^2 and a depending portion i^3 having a guided engagement in the bracket slot h . A spring k is applied in compression between said member i and one g of the guide lugs for normally maintaining the slidable feeler bar in its position of projection toward the shuttlebox.

O represents a rockshaft horizontally mounted parallel with the length of the breast beam and lay, and at right angles to the length of the feeler slide bar, the same being supported and journaled in the lugs m m therefor. This rockshaft has at one end an upstanding lever q provided with a stud q^2 which is engaging with the bifurcated upper portion of the member i which is affixed on the feeler slide bar, while at its other end the said rockshaft has another lever arm t , which is in position for engagement with the actuating arm b of the tilt-able member carried on the weft fork slide.

25 The shuttle box has its side toward the breast beam made with an aperture r , and the bobbin R of the loom shuttle S for the purposes of this invention is constructed in the particular manner especially shown in 30 Figs. 3, 7 and 8, that is, the bobbin having the butt portion u of frusto-conical shape and the stem portion u^2 of reduced diameter, has within said butt end portion a longitudinal recess v , the depth of which toward the butt end of the bobbin is as great as that of such recess where the frusto-conical portion adjoins the stem. In other words, the base of the recess is parallel with the axes of the bobbin for its entire length.

35 40 The bobbins are so wound that when nearly exhausted of thread, after all of the thread has been unwound off from the frusto conical butt portion, there is still a remnant of a few yards on the stem of the bobbin as represented at w in Fig. 2; and it is, of course, apparent that when the bobbin is full or partially full, the thread thereon spans the recess or cavity v at the bobbin butt, and serves as means through 45 50 which a forcing movement is imparted to the feeler slide bar.

55 While the loom is running with an amplitude of thread on the bobbin, the lay at each beat-up will cause the thread filled bobbin in the shuttle thereof to strike and forwardly force the feeler bar, resulting in the oscillation of the rockshaft, the downswing- 60 ing of the actuating arm b of the tilttable member J and the moving of the abutment e of such member out of the path of move- 65 ment of the weft hammer, all, of course, with the result of causing no stoppage of the loom. But when the bobbin thread shall have become nearly exhausted,—so that none thereof is around the recessed coni-

cal butt end of the bobbin, and only enough for a very few picks around the stem of the bobbin,—the lay in presenting the shuttle and the bobbin thereof in juxtaposition with the end of the feeler bar, causes such relation of the parts that the bobbin is carried comparatively axially close to the end of the feeler bar and without effect of slidably moving the same; and consequently the rockshaft not being oscillated and the tilt-able member J not being swung, the weft fork slide will be forwardly forced under the stroke of the weft hammer for operating the shipper and stopping the loom, thereby giving opportunity for bobbin re- 75 80 85 replenishment before any possibility of loss of a pick.

It is to be especially brought to attention that by having the base of the bobbin recess as deep or near the axes of the bobbin at the end of such recess toward the bobbin butt, any rebound of the shuttle at the time of striking the picker, will not result in any detrimental effect for unduly causing, when there is an absence of weft thread at the recessed butt end of the bobbin, the undue movement of the feeler slide bar to displace the tilttable member when in fact it should remain in its position to receive the stroke of the weft hammer.

The bobbin at its frusto-conical butt portion as shown in Fig. 8, has the recess v duplicated at diametrically opposite sides thereof so that it is immaterial as to which side of the bobbin is placed in the shuttle 100 forwardly thereof.

I have constructed some of the stop motions in accordance with this invention with a slightly different arrangement as represented in the view of the modification, Fig. 6, that is I have arranged the tilttable member J on the weft fork slide C with its actuating arm b rearwardly or toward the lay and with its tail or abutment e reversed or forwardly, and at a little distance ahead of the weft fork abutment a ; and correspond- 105 110 115 ing to this slightly different arrangement I provide a specially constructed weft hammer, that is one having in addition to the usual portion w for striking the weft fork abutment, an extension y for coaction with the abutment of the tilttable member J .

The bracket made in the adjustable portions s and s^2 confined in their given separations by the bolt and slot construction indicated at s^3 , s^4 , enables the positioning of the feeler slide bar properly for coaction with bobbins which may be of different dimensions or which in the operation of the shuttle relatively to the picker mechanism may not always have their "home" positions in the shuttle box exactly alike; and it is perceived that the member i by being adjustable on the feeler slide bar, and having a limitation at its normal position 120 125 130

against the lug *f*, constitutes a provision whereby the engagement end of the feeler may be nicely positioned to accord with the swing of the lay.

5 I claim:—

1. In a loom, in combination, the breast beam, the lay provided with the shuttle box, and the shuttle therefor, the weft fork slide, the shipper with which said slide coacts mounted on the breast beam and the weft hammer, a tilttable member, pivotally mounted on the slide, having an abutment adapted to be engaged by the weft hammer, and having an actuating arm, a bracket supported at the end of the breast beam opposite the location of the shuttle box and having upstanding apertured lugs and having a straight guiding slot therein, a feeler slide bar slidably mounted through said lugs adapted to be successively moved by the thread of the bobbin when present thereon and having a member adjustably confined thereon provided with an upstanding bifurcated portion and with a depending portion having a guided engagement in the slot of said bracket, a spring in compression between said feeler slide bar member and one of said lugs, a horizontal rockshaft having at one end an upstanding lever provided with a stud in engagement with the said bifurcated portion of the feeler slide bar member and having at its other end another lever arm for coaction with the actuating arm of said tilttable slide carried member. 55
2. In a loom, in combination, the breast beam, the lay provided with the shuttle box, and the shuttle therefor, the weft fork slide, 60

the shipper with which said slide coacts mounted on the breast beam and the weft hammer, a tilttable member, pivotally mounted on the slide, having an abutment adapted to be engaged by the weft hammer, and having an actuating arm, a bracket supported at the end of the breast beam opposite the location of the shuttle box and having upstanding apertured lugs and having a straight guiding slot therein, a feeler slide bar slidably mounted through said lugs adapted to be successively moved by the thread of the bobbin when present thereon and having a member adjustably confined thereon provided with an upstanding bifurcated portion and with a depending portion having a guided engagement in the slot 50 of said bracket, a spring in compression between said feeler slide bar member and one of said lugs, a horizontal rockshaft having at one end an upstanding lever provided with a stud in engagement with the said bifurcated portion of the feeler slide bar member and having at its other end another lever arm for coaction with the actuating arm of said tilttable slide carried member.

Signed by me at Springfield, Mass., in presence of two subscribing witnesses.
